UNITED STATES PATENT OFFICE.

JAMES G. HARDIE, OF CANTON, NEW YORK.

PAPER-CUTTING MACHINE.

No. 823,119.

Specification of Letters Patent.

Patented June 12, 1906.

Application filed March 28, 1905. Serial No. 252,595.

To all whom it may concern:

Be it known that I, JAMES G. HARDIE, a citizen of the United States of America, and a resident of the city of Canton, county of 5 St. Lawrence, State of New York, have invented certain new and useful Improvements in Paper-Cutting Machines, of which the following is a specification.

My invention relates to paper-cutting machines, and more particularly to that class of paper-cutting machines which are driven by power and are adapted to cut stacks of paper of various dimensions as well as to trim books and perform other similar kinds of work.

15 The object of my invention is to provide a machine of this class which shall be simple and effective in its construction and operation, which shall be capable of handling a wide variety of work more expeditiously and 20 conveniently than has been possible with the machines heretofore in use, and one in which special provision is made to prevent injury to the paper while it is being held or clamped for the operation of cutting.

25 My invention consists in providing a suitable framework which comprises, essentially, two side uprights secured to a horizontal table or bed which is adapted to receive the paper in stacks or other form, in providing 30 vertical guides which extend above the table, mounting a cutter-bar in said guides and connecting it to cranks secured to a crank-shaft which is journaled in the frame; in transmitting power to said crank-shaft by

35 means of elliptic gears from a shaft which is driven at a uniform speed, so that the descent of the cutter-bar consumes a greater amount of time than its ascent; in providing a power-clamp and means for causing the 40 clamp to descend in advance of the knife until it strikes the paper and means for causing the clamp to remain in contact with the paper until the knife is free and clear above it on its return stroke; in providing means for

45 varying the pressure exerted by the clamp upon the paper; means for increasing the pressure of the clamp upon the paper in successive increments of predetermined amount between the times when the clamp and the 50 knife first strike the paper, the organization of the parts being such that the excessive pressure produced when the motion of the clamp is arrested by first coming in contact with the paper—that is, when the friction begins to slip—is eliminated or reduced to a

55 harmless amount, and in the novel construc-

tion of the subclamp and means for operating it.

My invention consists, further, in providing a novel means for starting the machine and automatically stopping it at a fixed point in the cycle of operations, in a novel construction of the gage mechanism and means for actuating the same, and in other novel features to be hereinafter more particularly pointed out and described.

In the drawings accompanying and forming part of this specification, Figure 1 is a side view of the machine. Fig. 2 is a plan, partially in section, on line 2 2 of Fig. 1. Fig. 3 is a front elevation, partially in section, on line 3 3 of Fig. 1. Fig. 4 is a section on line 4 4 of Fig. 3. Fig. 5 is an enlarged section of the subclamp. Fig. 6 is a bottom view of a portion of the subclamp. Figs. 7 and 8 are 75 enlarged sections taken on line 7 8 of Fig. 13, showing different operative positions of the main clamp-bar-actuating mechanism. Fig. 9 is a partial section through the cutter-bar and blade and clamps, showing parts in different operative positions. Fig. 10 is a partial plan view of the back gage mechanism arranged for trimming books. Fig. 11 is a side view of the same, and Fig. 12 is a section on line 12 12 of Fig. 10. Fig. 13 is a partial 80 section through the rock-shaft 70, friction-cylinder 71, and the oscillating frame, showing one of the hooks 88 drawn outwardly to its non-engaging position.

The reference characters are used in the 90 same sense throughout the drawings and specification.

The main framework of the machine consists, essentially, of the uprights 1 at the sides of the machine and the table or bed 2. The 95 uprights are provided with extensions 3, which are located near the front of the machine and extend some distance above the table and serve the purpose of guides for the cutter-bar and the clamp-bars. These extensions are tied together by a transverse girder or beam 4. A represents a stack of paper.

Numeral 5 represents the cutter-bar. It has the usual cutter-blade 6 secured to it, and it is provided at its ends with balls 7 for the upper ends of the connecting-rods 8. A link 9 is pivoted to the beam 4 and the cutter-bar 5 in the usual manner to give the cutter-bar a transverse motion, as is well understood.

10 represents a crank-shaft which has the cranks 11 secured to its ends. These cranks

are provided with balls 12 for the lower ends of the connecting-rods 8.

13 is an elliptic gear secured to the crank-shaft, and it is engaged by the corresponding elliptic gear 14, mounted on the shaft 15. The elliptic gear 13 is so located on the crank-shaft 10 that that portion of the pitch-line of said gear having the smallest radius is in engagement with that portion of the gear 14 of greatest radius at the time when the cutter-bar is about in the middle of its ascending stroke, from which it results that the velocity ratio between the crank-shaft 10 and the intermediate shaft 15 is constantly changing and is greatest during the ascent of the cutter-bar and least during its descent.

I prefer to so form the elliptic gears that the ascent of the cutter-bar shall take place during about one hundred degrees of the revolution of the intermediate shaft 15 and its descent during the remaining two hundred and sixty degrees. The purpose of this construction is not merely to obtain a relatively quick return and slow descent of the cutter-bar, but also to obtain a more uniform descent. When the crank-shaft is driven at uniform speed, the cutter-bar moves at highest speed at the middle of its stroke, with the result that when the cutter-blade strikes a stack of paper near the middle of its descending stroke it partakes of the nature of a blow, causing severe strains upon the machine. It will be seen that by means of my improved construction the machine may be run at much higher speed and the commencement of the cut for stacks of different heights will be much more uniform than with the construction heretofore in use.

The gear 16, secured to the shaft 15, engages the pinion 17 on the shaft 18, on which latter shaft is also secured the gear 19, which engages the pinion 20, loosely mounted on the shaft 21. The pinion 20 is secured to a clutch 22. The clutch 22 is preferably some form of friction-clutch, and it may be of any approved construction.

23 is a cone slidably mounted on the shaft 21, and it is engaged by the lever 24 in such a way that when the cone 23 is moved away from the clutch 22 the engagement of the lever 24 with the cone 23 will put the clutch into action and cause the pinion 20 to revolve with the shaft 21.

25 is a groove in the cone 23, which is engaged by the pin 26, secured to the lever 27, which is mounted on the rock-shaft 28. When the rock-shaft 28 is turned to the left, the clutch 22 is thrown into action, and when it is turned to the right it is thrown out of action.

The lever 29 is rigidly secured to the shaft 28, and it is provided with a lug 30 and set-screw 31. The lever 32 is mounted on the shaft 28, and its position thereon is adjusted by means of the set-screw 31. A weighted

arm 33 is loosely mounted on the shaft 15 beside the gear 16, and a lug 34 is secured to the gear 16 in the path of the weighted arm 33, so that as said gear revolves the lug 34 will engage the weighted arm 33 and lift it to its highest position, after passing which, however, it drops by gravity and strikes the lever 32 on the shaft 28, thereby turning said shaft and moving the cone 23 toward the clutch 22 and throwing said clutch out of engagement.

It is thus seen that the clutch 22 is thrown out of engagement at a predetermined point in the revolution of the shaft 15, this point being at the time when the cutter-bar has just returned to its highest position.

A hand-lever 35 is secured to the front end of the shaft 28. The machine is started by means of this hand-lever when the paper has been adjusted to a proper position, and it is automatically stopped by the weighted arm 33 as soon as the cutter-bar has returned to its highest position. A pinion 36 is secured to a clutch 37 and engages the gear 16. The clutch is operated by a cone 38 and lever 39, mounted on the rock-shaft 28 in the same manner as the clutch 22, except that the clutch 37 is thrown out of engagement when the clutch 22 is thrown in, and vice versa. The shaft 40, on which the clutch 37 is mounted, is stationary, and when the clutch is thrown into engagement it acts as a brake, tending to retard the motion of the gear 16, which is in engagement with the pinion 36.

The details of the clutches 22 and 37 are not shown, as they form no part of my present invention and as it is obvious that any of the well-known forms of friction-clutches which may be arranged to be thrown into and out of engagement by making proper connections with a movable member, such as the rock-shaft 28, would answer for the purpose. The belt-wheel 41 is secured to the shaft 21 and is adapted to be belted to any convenient source of power, and it is preferably made of sufficient weight to answer at the same time for the purpose of a fly-wheel.

Mounted in guides in the upright extensions 3 immediately behind the cutter-bar 5 is the main clamp-bar 42, and mounted immediately beneath the main clamp-bar 42 and adapted to move up and down the same guides is the subclamp 43. The subclamp 43 is adapted to be operated manually through connections which will presently be explained or mechanically and automatically by its engagement with the main clamp-bar 42, which descends upon the subclamp and forces the latter down upon the stack of paper to hold the same in position during the cutting operation. The subclamp is lighter compared with the main clamp-bar and its weight is counterbalanced by springs or otherwise, so that it always tends to rise and make contact with the bottom of the main

clamp, the normal position of the main clamp when the machine is at rest being at the top of its throw.

The subclamp consists of a longitudinal vertical web 44 and rearwardly-projecting fingers 45, (see Figs. 5 and 6,) and it has secured to its under surface an elastic shoe 46, preferably made of felt, leather, or other compressible material. At the front edge of the lower surface of the subclamp is a rib 47, which extends down below the main surface of the body of the subclamp a distance somewhat less than the thickness of the elastic shoe 46, so that when the subclamp exerts pressure upon the surface of the stack of paper the rib 47 will be out of contact with the paper. The purpose of the elastic shoe is to prevent creasing or indenting the paper sheets of the stack of paper when pressure is exerted upon the subclamp, and the purpose of the rib 47 is to present a straight metallic edge close to the line of the cut. Pivotally secured to the ends of the subclamp are the links 48, and pivotally secured to the lower ends of said links are the levers 49, which latter are rigidly attached to the rock-shaft 50.

A hand-lever 51 is pivotally mounted on the bracket 52, secured to the front of the machine, and the said hand-lever has a forked end which engages a pin in the lever 53, secured to the rock-shaft 50. A lever 54 is secured to the rock-shaft 50, and a spring 55 is attached to the end of said lever of sufficient strength to raise the subclamp and keep it in contact with the main clamp-bar 42. A lever 56 is also secured to the rock-shaft 50 and connected, by means of the links 57, to the foot-treadle.

As will be apparent from the above explanation the subclamp may be brought down upon the paper either by the hand-lever 51 or by the foot-lever 58, and the direction of the motion of both the hand-lever and the foot-lever is the same as that of the subclamp. The purpose of having the subclamp operate independently of the main clamp-bar is to enable the operator to bring the subclamp down to the stack of paper, so as to determine exactly where the line of cut is going to take place before the power-clutch is thrown into action.

The main clamp-bar 42 is of sufficient strength to give it great rigidity. It is provided with rearward projections 63, corresponding to the rearwardly-projecting fingers 45 of the subclamp and its lower surface is planed so as to accurately fit the upper surface of the subclamp with which it makes contact. The main clamp-bar 42 is provided with a stud 60, which is mounted on a roller 61, which roller overhangs the cutter-bar 5, so that when the cutter-bar rises its top surface will engage the roller 61 and carry with it the main clamp-bar and the subclamp. At all times except when the subclamp is oper-

ated manually the subclamp and the main clamp-bar act together as a single member. The distance between the cutting edge of the knife 6 and the top surface of the knife-bar is such that when the knife-bar engages the roller 61 the cutting edge of the knife shall be above the lower surface of the clamp. This insures the knife being free and clear above the top of the stack of paper before the clamp has been withdrawn therefrom, thus preventing any disturbance of the stack which might result from the movement of the knife in contact with the front face of the stack if the stack was not secured by the clamp.

At its ends the clamp-bar 42 is connected with the links 64 by means of the binding-screws 65 and the adjusting-screws 66. The links 64 are provided at their lower ends with elongated slots 67, in which operate the studs 68, fixed to the levers 69, said levers being keyed to the rock-shaft 70. The clamp in the drawings is shown resting upon a stack of paper, a cut having just been made and the cutter-bar being in about the middle of its return or upward stroke.

The clamp-bar moves downward from its highest position with the cutter-bar by gravity, carrying the subclamp with it, the lower or contact surface of the subclamp being always slightly in advance of the cutting edge of the knife-blade until its movement is arrested by contact with the paper, at which point and just before the cutting edge of the knife-blade has reached the paper the stud 68 in the lever 69 engages the end of the slot 67, bringing the appropriate pressure to act upon the clamp-bar by means of the friction mechanism which I will now proceed to describe.

Rigidly secured to the rock-shaft 70 is a friction-cylinder 71, and mounted on this friction-cylinder are a plurality of friction-clamps each consisting of an upper piece 72 and a lower piece 73, united to the former by means of bolts 74 and 75. The cylindrical bores of the friction-clamps are provided with a lining 76, of leather or other suitable material. The upper part 72 of the friction-clamps is provided with rearwardly-projecting ends 77, which carry the adjustable banking-bolts 78 and forwardly-projecting arms 79, which carry the adjusting-screws 80.

Pivotally mounted on the rock-shaft 70 is an oscillating frame which consists of the side members 81, joined by an end piece 82 and by the shafts 83 and 84, and each side piece is provided with an arm 85, carrying the pin 86, which engages the cams 87, keyed to the shaft 15. Mounted on the shaft 83 of the oscillating frame are a plurality of hooks 88 equal in number to the number of friction-clamps, each hook being adapted to engage one of said clamps. The hubs of the hooks 88, which encircle the shaft 83, are split and provided with a binding-screw, which may be adjusted to give a certain amount of fric-

tion between the hub and the shaft for the purpose of causing the hooks to remain in whatever position they are left. A rod 89 is pivotally attached to each of said hooks and 5 extends forward through the front plate 82 of the oscillating frame, where it terminates in a knob conveniently accessible to the operator of the machine.

As will be apparent from the drawings, the 10 revolution of the cam 87 will cause the oscillating frame to oscillate, and during the downward movement of said frame each hook 88 which is thrown inward to its engaging or operative position, as shown in Fig. 4, will engage 15 its corresponding friction-clamp and carry said clamp with it and by virtue of the friction between the friction-clamp and the friction-cylinder 71 will cause the cylinder and the rock-shaft 70 to move in unison with the oscillating frame until the engagement 20 of the pin 68 with the end of the slot 67 and the engagement of the subclamp 43 with the paper arrest the motion of the rock-shaft 70, from which point the friction-clamp will 25 slip upon the friction-cylinder and cause a certain pressure to be exerted by the subclamp upon the paper.

It will also be apparent that if any one or 30 more of the hooks 88 is withdrawn from its engaging position the corresponding friction-clamps will be thrown out of action and exert no influence upon the subclamp.

In the operation of power paper-cutting machines it is desirable to have the clamp exert as great a pressure as possible upon the paper without producing indentations there-in, and if the clamp is adjusted to give the proper pressure for a broad cut it will be found to be excessive for a narrower cut. It will 35 be seen that by means of my construction the operator may quickly and conveniently modify the action of the clamp to suit the requirements as they arise.

During the upward movement of the oscillating frame the friction-clamps are returned 40 to their normal position by the engagement of the adjusting-screws 80 with the shaft 84. The banking 90 is provided to arrest the movement of the friction-clamps at the 45 proper point on their return, the adjusting-screws 78 in the rear ends 77 of the friction-clamps being adapted to engage the banking 90 for this purpose.

In all kinds of friction devices what is 50 known as the "starting friction" is far in excess of what is usually termed the "running friction," or the friction between the surfaces after they have begun to slip. It is, however, the running friction, or the friction which 55 takes place during the slipping of the friction-clamps upon the friction-cylinder, which is relied upon to hold the paper during the cutting operation, from which it follows that if the friction device of a paper-cutting machine 60 is so adjusted as to give the maximum

clamping action obtainable without injury to the paper while the friction is slipping—that is, while the cut is actually taking place—the starting friction being far in excess of the running friction will be so great as to injure the paper. In order to minimize the effect of this peculiarity of friction, I arrange the friction-clamps so that they come into operation successively, thereby avoiding the excessive starting friction which would occur if all of the friction-clamps came into action simultaneously. This is accomplished in the following manner:

The adjusting-screws 80, which are engaged by the shaft 84 during the return of the friction-clamps by the upward movement of the oscillating frame, are so adjusted as to leave the upper surfaces of the friction-clamps which are engaged by the hooks 88 at successively-increasing heights, the engaging ends 35 of the hooks being arranged at uniform heights, so that during the downward movement of the oscillating frame after the rock-shaft 70 has been arrested by the contact of the subclamp with the paper the several friction-clamps will come into action successively, as will be clearly seen in Figs. 7 and 8.

Mounted on the table 2 to the rear of the clamp-bars are the movable gage-brackets 91, 92, and 93. These gage-brackets are provided with rollers 94 to facilitate their movement back and forth. Each gage is provided also with vertical webs 95, in which are longitudinal slots for the reception of the clamping-bolts 96. By means of this connection 100 the gage-frames may be adjusted back and forth relative to each other, as shown in Figs. 10, 11, and 12, where the central gage-frame 92 is considerably in advance of the side-frames 91 and 93. The purpose of this construction is to provide for the simultaneous trimming or cutting of stacks of different dimensions—such, for instance, as trimming the different edges of books and pamphlets.

In the figures referred to, B represents books 110 whose edges c, d, and e are to be trimmed or cut in the order named. For this purpose the gage-frames 91, 92, and 93 will be adjusted so as to bring the front or working face of the gage-fingers in proper relation, so that a single cut will trim the end C of the books gaged by the frame 91, the sides D of the books on the frame 92, and the ends E of the books on the frame 93. The books at the sides will be guided and aligned by the side guides 110, as is usual. In order, however, to provide for the trimming of a greater number of books at a time, I provide intermediate guides 111 and 112, which are joined by a transverse member 113, adapted to be secured in position by the bolts 114 or in any other convenient manner.

In order to steady the stacks, I provide a top guide 115, which is also secured in position by the bolts 114 or in any other conven- 130

ient manner, and in order to provide for a greater range of adjustment between the three gage-frames 91, 92, and 93, and especially in order to provide for trimming very narrow books, I provide fillers 116, which come between the top guide 115 and the transverse or connecting bar 113.

A shaft 97 is mounted in each of the gage-frames some distance above the surface of the table, and upon this shaft a number of gage-fingers 98 are pivotally mounted. The lower surface 99 of the gage-fingers rests upon the surface of the table, and the front face 100 is at right angles thereto.

15 The gage-fingers are loosely mounted on the shafts 97 and may move independently of each other; and they are brought by gravity down into contact with the surface of the table. The purpose of this construction is to insure contact between each of the gage-fingers and the surface of the table even if there are irregularities in the latter, and by having the center of the shaft 97, on which the gage-fingers are pivoted, located above the center 25 of the gage-surface of the gage-fingers the pressure against the gage-surface tends to keep the gage-fingers down in contact with the surface of the table.

30 A transverse yoke 101 is secured to the central gage-frame 92 and has threaded holes in its ends, which engage the screws 102. These screws are mounted in brackets at the sides of the table and have fixed to their rear ends beveled pinions 103, which mesh with 35 the pinions 104, fixed to the shaft 105, on which is also secured the spiral gear 106. The spiral gear 106 meshes with the spiral gear 107, which is mounted on the shaft 108, which extends from the rear of the machine 40 underneath the table to the front end thereof, where a hand-wheel 109 is mounted.

As will be apparent from the drawings, the gage may be moved forward or backward by turning the hand-wheel 109. By means of 45 this construction I avoid the usual central slot in the table, and by the engagement of the yoke 101 with the screws 102 at points widely separated the accurate alinement of the gages is easily adjusted and maintained.

50 Having thus described my invention, what I claim is—

1. In a paper-cutting machine the combination with a clamp-bar of a plurality of friction devices for actuating said clamp-bar and means for separately throwing said friction devices into and out of action.

2. In a paper-cutting machine the combination with a clamp-bar, of a friction mechanism adapted to actuate said clamp-bar provided with means for automatically increasing the power of said clamp-bar after its motion has been arrested.

3. In a paper-cutting machine the combination with a clamp-bar of a frictional clamp-bar-actuating mechanism provided with

means for varying the power which said clamp exerts upon the paper in a predetermined manner.

4. In a paper-cutting machine the combination with a clamp-bar of a plurality of clamp-bar-actuating devices each capable of producing a clamping action of certain power and means for bringing a plurality of said clamp-bar-actuating devices successively into action.

5. In a paper-cutting machine the combination with a clamp-bar of a power-actuated member, a plurality of friction devices adapted to connect said power-actuated member to said clamp-bar and means for independently throwing said friction devices into and out of action to regulate the power of the clamping action of said clamp-bar.

6. In a paper-cutting machine the combination with a clamp-bar, a power-actuated member, a plurality of friction devices adapted to connect said power-actuated member to said clamp-bar and means for independently throwing said friction devices into action; of means for increasing the power of 90 said clamp-bar after its motion has been arrested by contact with the paper.

7. In a paper-cutting machine the combination with a clamp-bar of a power-actuated member, a plurality of friction devices adapted to connect said power-actuated member with said clamp-bar and means for severally throwing said friction devices into action, and causing them to act successively upon said clamp-bar.

8. In a paper-cutting machine the combination with a clamp-bar of a rock-shaft, connections between said rock-shaft and said clamp-bar and plurality of friction devices each adapted to move said rock-shaft with a 105 predetermined power and means for putting said friction devices into action independently.

9. In a paper-cutting machine the combination with a power-actuated clamp-bar, of a 110 rock-shaft, connections between said rock-shaft and said clamp-bar, a plurality of friction devices each adapted to move said rock-shaft with a predetermined power, means for putting said friction devices into and out of 115 action independently and causing said friction devices to exert power upon said clamp-bar successively.

10. In a paper-cutting machine the combination with a clamp-bar, a rock-shaft and connections between the rock-shaft and clamp-bar, of a power-actuated reciprocating member a plurality of frictional connections between the reciprocating member and rock-shaft, and means for throwing said frictional connections into and out of action 125 severally.

11. In a paper-cutting machine the combination with a clamp-bar, a rock-shaft and connections between the rock-shaft and 130

clamp-bar, of a power-driven reciprocating member pivotally attached to the said shaft, devices in frictional engagement with said rock-shaft and means to engage and disengage said power-driven member and said devices.

12. In a paper-cutting machine the combination with a clamp-bar, a rock-shaft and connections between said clamp-bar and said rock-shaft, of a friction-cylinder secured to said rock-shaft, a friction member mounted on said friction-cylinder in frictional engagement therewith, a power-driven reciprocating member and means for operatively engaging and disengaging said reciprocating member with said friction member.

13. In a paper-cutting machine the combination with a clamp-bar, a rock-shaft and connections between said clamp-bar and said rock-shaft, of a friction-cylinder secured to said rock-shaft, a plurality of friction members mounted on said cylinder in frictional engagement therewith, a power-driven shaft having a cam mounted thereon, a reciprocating member actuated by said cam and means for severally engaging and disengaging said friction members from said reciprocating member.

14. In a paper-cutting machine the combination with a clamp-bar, a rock-shaft and connections between said clamp-bar and said rock-shaft, of a friction-cylinder secured to said rock-shaft, a plurality of friction members mounted on said cylinder in a frictional engagement therewith, a power-driven shaft having a cam mounted thereon, a reciprocating member actuated by said cam, a means for causing said friction members to engage said reciprocating member consecutively after the descent of the clamp-bar has been arrested by coming into contact with the paper.

15. In a paper-cutting machine the combination with the knife-bar, of a crank-shaft, a crank thereon, connections between said crank and said knife-bar, a power-driven shaft geared to said crank-shaft, a clamp-bar, a rock-shaft, connections between said clamp-bar and said rock-shaft, a cam upon said power-driven shaft, a reciprocating member actuated by said cam, a frictional connection between said reciprocating member and said rock-shaft and means for operatively engaging and disengaging said frictional connection.

16. In a paper-cutting machine the combination with a knife-bar, a crank-shaft, a crank thereon, connections between said crank and said knife-bar, of a power-driven shaft geared to said crank-shaft, a clamp-bar, a rock-shaft, a plurality of friction devices connecting said reciprocating member and rock-shaft, connections between clamp-bar and said rock-shaft.

17. In a paper-cutting machine the combination with a power-actuated cutter-bar and

a power-actuated clamp-bar, of a subclamp located beneath said clamp-bar, a rock-shaft located beneath said subclamp, levers fixed to said rock-shaft, links connecting the ends of said levers with the ends of said subclamp, a hand-lever pivoted in front of said rock-shaft and connections between said hand-lever and said rock-shaft whereby said hand-lever and said subclamp move in the same direction.

18. In a paper-cutting machine the combination with a flat table supported by a suitable framework, of a cutter-bar and clamp-bar operatively mounted across the forward end of said table, a back gage mounted on said table to the rear of said clamp-bar, screws mounted at and parallel to the longitudinal sides of said table, a yoke secured to said back gage in threaded engagement with said screws, a transverse shaft mounted on the rear end of said table in geared connection with said screws, a shaft in geared connection with said transverse shaft extending beneath said table to the front of said machine and a hand-wheel on said last-named shaft.

19. In a paper-cutting machine the combination with a shaft adapted to be continuously driven, of a cutter-bar, actuating mechanism for said cutter-bar, a clutch adapted to connect said continuously-driven shaft with said actuating mechanism, a weight pivotally mounted on a member driven by said clutch and means actuated by said weight to throw said clutch out of engagement at a predetermined point in the revolution of said member.

20. In a paper-cutting machine the combination with the cutter-bar, a crank-shaft, cranks on said shaft, and connecting-rods between said cranks and said cutter-bar, of a continuously-driven shaft, geared connections between said continuously-driven shaft and said crank-shaft, a clutch between said continuously-driven shaft and said geared connections, a weighted arm mounted concentrically with an element of said geared connections, means on said element adapted to lift said weight during half a revolution of said element and permitting said weight to drop away from said means after it has passed the highest point in its revolution and means engaged by said weight during its descent, to throw said clutch out of engagement.

21. In a paper-cutting machine the combination with a cutter-bar and a crank-shaft for operating said cutter-bar, of a continuously-driven shaft, an intermediate shaft geared to said crank-shaft and to a clutch member on said continuously-driven shaft, of a weighted arm on said intermediate shaft, a lug secured to said intermediate shaft adapted to engage said weighted arm during the ascending half of its revolution and permitting it to drop during the descending half of its revolution by gravity, and means engaged by said arm to throw said clutch out of engagement.

22. In a paper-cutting machine the combination with the cutter-bar and crank-shaft adapted to operate said cutter-bar, of a power-driven shaft, a clutch member mounted on said power-driven shaft, geared connections between said clutch member and said crank-shaft, a friction-brake and means for automatically unclutching said power-driven shaft from said geared connections, and throwing said friction-brake into action to arrest the motion of said crank-shaft at a predetermined point in a revolution.

23. In a paper-cutting machine the combination with the cutter-bar-actuating mechanism, of a friction-clutch composed of two members one of which is held against rotation, the other being secured to a rotating element of the cutter-bar-actuating mechanism, and means for automatically engaging said clutch members to stop the machine.

24. In a paper-cutting machine the combination with a cutter-bar-actuating mechanism, of a friction-clutch composed of two members, one of which is in geared connection with said operating mechanism, the other being held against rotation, and means for automatically engaging said members to stop the machine.

25. In a paper-cutting machine the combination with a cutter-bar-actuating mechanism, of a driving-shaft and a stationary shaft each carrying friction-clutch members in geared connection with said actuating mechanism, coacting clutch members rotatably fixed upon said driving-shaft and said stationary shaft respectively, and means connecting said coacting clutch members whereby the engagement of one is accompanied by the disengagement of the other.

26. In a paper-cutting machine, the combination with a power-actuated cutter-bar and a clamp, of engaging means between said cutter-bar and said clamp, whereby said clamp is raised by said cutter-bar, and lowered by gravity in contact therewith, and a friction mechanism adapted to act upon said clamp-bar before and during the cutting operation.

27. In a paper-cutting machine the combination with a clamp-bar of a downwardly-projecting rib extending along the front edge of its lower surface and an elastic shoe behind said rib.

28. In a paper-cutting machine the combination with a table, of a back gage extending transversely across said table made in a plurality of sections adjustable relative to each other, a transverse yoke secured to one of said sections, and means for operating said yoke forward and backward.

29. In a paper-cutting machine, the combination with a power-actuated knife and clamp, of means for automatically causing the clamp to descend in advance of the knife, a friction mechanism adapted to cause the clamp to exert pressure upon a stack of paper after its descent has been arrested, means for releasing the pressure upon the clamp after the cut has been completed, and means permitting said clamp to remain in contact with the paper until after the cutting edge of the knife has risen above the stack on its return stroke.

In testimony whereof I have signed my name to this specification in the presence of two subscribing witnesses.

JAMES G. HARDIE.
